UNITED STATES PATENT OFFICE.

E. STILLMAN BABCOCK, OF MILTON, WISCONSIN, ASSIGNOR OF ONE-HALF
TO A. S. MAXSON, OF SAME PLACE.

VENT-HOLE CLOSER FOR PUMPS.

SPECIFICATION forming part of Letters Patent No. 349,680, dated September 28, 1886.

Application filed June 28, 1886. Serial No. 206,499. (No model.)

To all whom it may concern:

Be it known that I, E. STILLMAN BABCOCK, a citizen of the United States, residing at Milton, in the county of Rock and State of Wisconsin, have invented a new and useful Improvement in Vent-Hole Closers for Pumps, of which the following is a specification.

My invention is an improved vent-hole closer for pumps; and it consists of the peculiar construction, combination, arrangement, and adaptation of parts, substantially as hereinafter described, and specifically pointed out in the claim.

The object of my invention is to provide a device to be attached to the pump-pipe and be operated from the top of the well to open and close the vent of the pump, so as to allow the water to run out of the pump into the well and prevent it from freezing in the pump. A further object is the provision of means for this purpose which can be attached to any ordinary pump at a very small expense, which will be strong and durable and thoroughly efficient for the purposes intended. I attain these objects by the means illustrated in the accompanying drawings, in which—

Figure 1 is a top plan view of my device secured in place upon the pipe of a pump. Fig. 2 is a perspective view of my device detached from the pump. Fig. 3 is a longitudinal section on the line $x x$, Fig. 1.

Referring by letter to the drawings, A designates a metal band adapted to pass around the pump pipe or cylinder, and provided on one side with a screw-threaded opening, in which opening works a set-screw, B, which bears against the pipe or cylinder, and secures the band rigidly to the same. One of the free ends of this encircling band A is notched or cut out at a , and also provided with the upwardly-extending arm or guide C. In the other free end of the band A is secured a screw, pin, or bolt, D, which projects outwardly from the said free end of the band, and forms a pivot for a cut-off, E. A coiled spring, d, is placed on the pivot D, and bears against the cut-off E at one end, for the purpose presently described. This cut-off E has secured to it at a suitable point a rubber or leather block, e, which is adapted to fit over the vent-hole in

the pipe and effectually close the same. The other end of this cut-off E fits or rests in the notch a , provided in the band A, and is also provided with an opening or eye, e' , to enable a cord or wire or like means to be attached to the said cut-off to lift the same when desired. This cut-off also has depending from its under side about the center an ear or projection, e^2 , which forms a guard.

The operation of my invention will be readily understood from the foregoing description, when taken in connection with the drawings.

The device is rigidly secured in place by means of the band and set-screw, and the leather or rubber block or stopper is placed over the vent-hole by the cut-off, and the cord or wire which connects with the cut-off is passed up above the top of the well or cistern, so as to be in easy reach. When it is desired to give vent to the pipes and prevent the water from freezing therein, it is only necessary to draw on the cord, which elevates the cut-off, opening the hole in the pipe and allowing the water therein to run out and back into the well. The guard provided on the cut-off appears in front of the opening, and prevents the water from splashing and washing the sides of the well. I provide the spring in connection with the cut-off, so that if the pressure is too great on the cut-off the spring will give and release the rubber or leather stopper from contact with the hole in the pipe.

It will be observed that I provide a device which can be secured to any pump employing a cylinder or pipe, and that the means provided for securing the same are thoroughly reliable, not likely to get out of order, and are cheap to manufacture.

Heretofore it has been the common practice to make a vent-opening in the pump below the frost-line, and in the spring of the year the pump must be taken out of the well to cork up or close the vent-opening. My device overcomes this objection, as it can be operated from the top of the well by means of the connection to open and close the opening, and does away with the necessity of lifting the pump from the well to accomplish this purpose.

Having thus fully described my invention, I claim—

The herein-described attachment for pumps, comprising the attaching - band A, open at one side, and provided with the clamp-screw B, the cut-off E, arranged across the open side 5 of the band and pivoted at one end to the band, a spring, d, bearing against the cut-off at the pivot-point, and a guard, e², depending from the cut-off, for the purpose set forth.

In testimony that I claim the foregoing as my own I have hereto affixed my signature in presence of two witnesses.

E. STILLMAN BABCOCK.
